United States Patent Office.

WILLIAM MORGAN, OF MIDDLEBROOK, VIRGINIA.

Letters Patent No. 97,793, dated December 14, 1869.

IMPROVED WASHING-MACHINE.

The Schedule referred to in these Letters Patent and making part of the same.

To all whom it may concern:

Be it known that I, WILLIAM MORGAN, of Middlebrook, in the county of Augusta, and State of Virginia, have invented certain new and useful Improvements in Washing-Machines, of which the following is a full, clear, and exact description, reference being had to the accompanying drawings, which make part of this specification, and in which—

Figure 1 is a perspective view of the machine;

Figure 2, a horizontal section of the same at the line *x x* of fig. 1; and

Figure 3, a plan view of the support for the tub and of the handle for oscillating it.

My invention relates to that class of machines with which an oscillating tub is used.

In the accompanying drawings, the frame A A is shown as made of a rectangular form.

The upper parts of two uprights, B B, mounted on this frame, are connected by the cross-bars C C, which also form guides for the slide-bars D D, and the lower parts of these uprights are connected by the cross-bars C, which also forms a support for the axle of the oscillator E, upon which the tub F rests, and with which it turns.

The slide-bars D D are connected at their upper ends by a cross-piece, G, which also forms a bearing for the lever H, and at their lower ends by a cross-piece, G', to which is attached a rubber, I.

A lever, H, vibrates vertically on a pivot, h, on one of the uprights B.

A stud, h, attached to this lever, bears upon the upper side of the cross-piece G.

The tub F has a corrugated bottom, f, and is also provided with guide-pieces, f' f'', which overlap the oscillator E, and thus hold the tub in place.

The oscillator consists of a paddle-shaped lever, E, having a cylindrical base, e, an axle, e', and a stop, e'', against which the tub rests.

The rubber I is composed of beaded rounds, which are attached to the cross-piece G', and may be either parallel to each other or radial to the axis of rotation of the tub.

The operation of the machine is as follows:

The cross-pieces G G', with the slide-bars D and rubber I, are first raised by hand, or by means of a suitable lever attached to one of the uprights, and may be supported by pins or otherwise while the tub is placed in position upon the oscillator, the supports may then be withdrawn, and the rubber descends and rests upon the material in the tub to be washed, and may be caused to press with any degree of force by means of the lever H.

Motion is then communicated to the tub by means of the oscillator lever, and the material in the tub is subjected to a rubbing action between the beaded rounds of the rubber and the corrugated bottom of the tub, closely resembling that of the knuckles upon the ordinary corrugated wash-board.

The guide-pieces f hold the tub firmly when turning, but are so constructed as to permit the tub to be lifted out of its place when necessary.

What I claim as my invention, and desire to secure by Letters Patent, is—

1. The combination of the depressing lever, the sliding frame, the rubber, the tub, and the oscillator, all constructed to operate as set forth.

2. The combination of the tub with the oscillator, constructed and operating as herein described.

In testimony whereof, I have hereunto subscribed my name.

WM. MORGAN.
